Primary Examiner—Martie Thompson**[57] CLAIM**

The ornamental design for a “paper clip with hook end and square end”, as shown and described.

DESCRIPTION

FIG. 1 is a front elevational view of a paper clip with hook end and square end, showing my new design, the rear elevational view being a mirror image thereof;

FIG. 2 is a left side elevational view thereof;

FIG. 3 is a right side elevational view thereof;

FIG. 4 is a top plan view thereof; and,

FIG. 5 is a bottom plan view thereof.
